UNITED STATES PATENT OFFICE

WILLIAM BEDDIE ROBERTSON, OF SHANGHAI, CHINA, ASSIGNOR TO STANDARD OIL COMPANY OF NEW YORK, OF NEW YORK, N. Y., A CORPORATION OF NEW YORK

APPARATUS FOR HEATING SOLDER

Application filed November 19, 1926. Serial No. 149,424.

The present invention relates to soldering machines and more particularly to a method and apparatus for heating solder in elongated pots.

5 Heretofore in the art it has been customary in heating the iron pots, containing solder for use in soldering the tops and bottoms of tin cans, to use a number of open kerosene oil burners located at intervals along the length 10 of the pot. Such apparatus is expensive to operate first because of the high cost of kerosene as compared with the low cost of fuel such as fuel oil and secondly because of the waste of heat occasioned by a multiplicity of 15 open burners.

The present invention eliminates these objections by mounting the solder pot upon a suitable furnace which may comprise a casing for enclosing the space about the lower side of 20 the pot and for directing the gases from the burner along the pot. The casing preferably is enclosed by suitable heat insulating material such as fire brick. A single burner adapted to burn low grade oil such as fuel oil, is 25 mounted at one end of the furnace to direct a flame along the bottom of the soldering pot and by reason of the confinement and direction of the gases the solder is uniformly heated throughout the length of the pot for application to containers. The proper operation 30 of the burners with this more or less viscous fuel is assured by utilizing the furnace gases to heat the fuel oil sufficiently to permit it to flow through the burners. Starting of the 35 furnaces is facilitated by an auxiliary supply of fuel of lighter constituency which may be utilized until the fuel oil is raised to the proper operating temperature.

40 An object of the invention is to reduce the burners and the fuel consumption thereof to a minimum in heating solder for top and bottom soldering machines.

Another object of the invention is to utilize 45 a low grade of fuel, preferably a by-product of petroleum refineries, in the heating of solder pots for use in top and bottom soldering machines, thereby decreasing the cost of fuel therefor.

50 A further object of the invention is to assure the proper operation of a number of

burners from a single supply of fuel oil by utilizing the furnace gases to raise the temperature of the fuel oil, thereby decreasing the viscosity thereof.

Other and further objects of the invention 55 will be obvious upon an understanding of the preferred embodiment about to be described, or will be indicated in the appended claims, and many advantages other than those herein specifically referred to will occur to one 60 skilled in the art upon employment of the invention in practice.

A preferred embodiment has been chosen 65 for purposes of illustration and description, and is shown in the accompanying drawings, 70 wherein

Fig. 1 is a side elevational view of a group 75 of furnaces, showing the burners operatively connected to a reservoir through which the fuel gases are by-passed for heating same;

Fig. 2 is a sectional view along the line 2—2 of Fig. 1 giving a plan view of a pair of furnaces preferably for bottom soldering and a sectional view of a pair for soldering tops on 80 the containers;

Fig. 3 is an end elevational view taken 85 from the right end of Fig. 1;

Fig. 4 is a sectional view taken along the line 4—4 of Fig. 2 illustrating details of the furnace;

Fig. 5 is a sectional view along the line 5—5 of Fig. 2 illustrating the form of soldering pots together with the associated supporting members;

Fig. 6 is an elevational view of the preferred form of burner assembled;

Fig. 7 is a longitudinal sectional view showing the parts of the burner proper, and

Fig. 8 is a longitudinal sectional view 90 showing details of the shield.

Referring to the drawings, there is shown a group of furnaces four in number, which are suitable for a double top and bottom soldering machine. Preferably the first pair of furnaces 1 are for soldering the top 95 seams of the tins, and the second pair of furnaces 2 are for soldering the bottom seams.

Each furnace preferably comprises a cast iron casing 4, comprising two castings 5 and 100

6, extending longitudinally of the furnace and supported in upright position to seat the outwardly flared portions 7 of the solder pot 8 on the upper edges thereof. The 5 lower edges of the castings 5 and 6 have inwardly extending flanges forming the shoulders 9 adapted to seat the arched supporting members 10 thereon. These members preferably are cast and have two legs 11 adapted to rest on the shoulders 9 with an upper horizontal portion 14. An arched web 15 is formed between two legs to give additional strength to these members which are disposed at intervals along the bottom 13 of the solder pot to supplement the supporting action of the upper edges of the casing 4 and in addition to hold the latter firmly in position. Preferably about six of these are utilized.

20 The casing 4 is mounted upon the upper part of the furnace and the lower part thereof is enclosed by suitable heat insulating material such as fire brick 16, preferably laid in fire clay. A flue 18 is provided having a 25 floor 19 also of fire brick, with the sides thereof recessed to provide supporting shoulders 20 for the casing 4. A pair of angle irons 21 extend longitudinally of the top of the furnace in contact with the outer sides of the casing 4 and are bolted thereto by means of the 30 stove bolts 24 securely to hold the casing in position. The ends of the casing 4 may be partially enclosed by means of the castings 23. For economy and convenience, the 35 portions of the furnaces 25 removed from the flue may be formed from ordinary brick laid in lime-cement mortar.

30 The floor of the flue (see Figs. 1, 4 and 5) is graded at the rear end thereof as shown at 27 to direct and to confine the gases adjacent the soldering pot. When the gases reach the 35 end of the pot they are directed outwardly in a horizontal direction into the adjacent chimney shaped extension 33 and upwardly into the pipe 29 leading from the extension to the flue 30 common to all of the furnaces. A 40 reservoir 31 for fuel oil is mounted on a platform 32 above the flue 30 and a by-pass 35 runs upwardly through the longitudinal 45 center of the reservoir and is extended outwardly from the top thereof horizontally to join the pipe 36 leading from the flue 30 to the chimney. Suitable dampers 37 and 38 are mounted in the pipe 36 and by-pass 35, 50 respectively, and are provided with adjustable weights 39 and 40 adapted to move the dampers in opposition to the springs 41 and 42 to control the temperature of the fuel oil in accordance with the weights attached to 55 the respective dampers.

60 At the front end of each furnace there are burners 45 preferably of the form described hereinafter, and these burners are connected to the conduit 47 leading from the reservoir 65 31 by means of the branch pipes 48. The flow

of oil through the burners and the temperature of the respective furnaces and solder pots are controlled by means of the valves 51. Compressed air may be furnished the burners through pipes 49 and controlled by valves 50.

70 Because of the fact that fuel oil, which is contemplated in the use of the present apparatus, is quite viscous when cold, there is provided herein a supplemental supply of oil in the tanks 52 of lighter grade which is connected to the burners through the check valves 55, pipes 56, check valves 57 and branch pipes 48. In starting the apparatus the burners are supplied with oil from the auxiliary tanks 52 until the flue gases, passing through the pipe 35, heat the fuel oil in reservoir 31 to the proper operating temperature.

75 While it is not desired to limit the broad concept of the present invention to any type of burner, a preferred form of burner is described herein which will give excellent results. The burner comprises a jet 60, screw threaded at its lower end for attachment to a suitable source of fuel supply and provided 80 with a continuous longitudinal passage 61 extending therethrough, said passage preferably decreasing in area as it approaches the end of the jet. An annular shoulder 62 is provided on the jet with screw threads 64 extending above the shoulder to accommodate a member 65 threaded thereon and forming a chamber 66 surrounding the fuel jet. The upper end of the member 65 is threaded to receive a plug 68 which, when screwed into 85 the end of the member 65, substantially closes the upper end of the chamber 66 leaving a 90 very narrow annular aperture 69 for the emission of air about the end of the jet. A suitable threaded aperture 70 may be provided in the side of the member 65 to facilitate the attachment of a tube, such as the pipe 49, leading to a compressed air supply. A shield 72 having apertures 75 for admission 95 of additional air to mix with the carburetted gases is mounted about the end of the fuel jet by telescoping the aperture 78 in the base thereof about the conical portion of the member 65. The aperture 73 at the upper end of the shield and the apertures 74 in the side 100 thereof afford suitable flame apertures for the burner.

105 In the operation of the burner, fuel oil is furnished through the passage 61, preferably though not necessarily it is moved by vacuum through the narrow opening 79 at the end thereof. Compressed air is admitted into the shield 72 through the annular outlet 69 between the jet 60 and the member 68. The air 110 rushing through this narrow annular passage about the end of the jet creates a vacuum which tends to draw the fuel through the opening 79 and in addition greatly facilitates the complete atomization thereof. The 115 120 125 130

sheld furnishes additional air which further dilutes and atomizes the carburetted fuel.

In the operation of the apparatus the solder pots are filled with solder and the burners are operated upon a relatively light grade of oil obtained from the auxiliary reservoirs 52, the temperature of the flame being regulated by means of the fuel valves 57 and the air valves 50, until the oil in the reservoir 31 has been heated by gases by-passed through the pipe 35. The oil from the auxiliary reservoirs 52 is then shut off by means of the valves 55 and the heated fuel oil supplied through the pipes 47 and branch pipes 48 by valves 51 and the burners regulated to give the desired degree of heat. From time to time the weights 39 and 40 are adjusted to maintain the fuel oil at the proper temperature to secure the most efficient operation of the burners. The flames of the burners are directed underneath the solder pots and the furnace flue encloses and maintains the gases adjacent the bottom of the pots. After traveling the entire length of the pots the gases are delivered to the flue 30 and a proper part thereof utilized for heating the fuel oil in the tank 31.

It will be seen that a very economical method and apparatus has been provided for heating solder pots by means of a low grade of fuel oil which may be a by-product of oil refineries, and that the quantity of this low grade oil used is reduced to a minimum. Further the parts of the furnaces are readily removable and replaceable so that wear and breakage may be readily repaired. Each furnace may be controlled individually and independently and all parts thereof are of rugged construction and fully capable of withstanding the rough usage to which it may be subjected.

As various changes may be made in the above embodiment without departing from the spirit of the invention, the description herein set forth is to be interpreted as illustrative and not in a limiting sense.

Having thus described my invention, I claim:

1. In a device of the class described, the combination of a plurality of furnaces for heating solder pots and the like, a fuel oil burner for each of said furnaces, a supply of fuel oil for said burners, and means including a by-pass for conducting a portion of the furnace gases into heating contact with said fuel oil.

2. In a device of the class described, the combination of a plurality of furnaces for heating solder pots and the like, a fuel oil burner for each of said furnaces, a supply of fuel oil for said burners, means for by-passing the furnace gases for heating said fuel oil, and devices for controlling the amount of gases by-passed to regulate the temperature of the fuel oil.

3. In a device of the class described, the combination of two pairs of furnaces for heating solder pots and the like, an oil burner for each of said furnaces, an oil tank for supplying fuel to said burners, a pipe extending through said tank, and means for by-passing furnace gases through said pipe to heat said oil. 70

4. In a device of the class described, the combination of two pairs of furnaces for heating solder pots and the like, an oil burner for each of said furnaces, an oil tank for supplying fuel to said furnaces, a common flue for said furnaces, a pipe extending through said tank, and means for by-passing furnace gases from said flue through said pipe to heat the oil in said tank. 75

5. In a device of the class described, the combination of an elongated solder pot, said pot having outwardly flared portions along opposite sides thereof, a supporting casing including side wall members adapted to engage said portions to support said pot, and additional supporting members carried by said side members and engaging the bottom of said pot at intervals. 80

6. In a device of the class described, the combination of an elongated solder pot, said pot having outwardly flared portions along opposite sides thereof, a supporting casing adapted to engage said portions to support said pot, supporting shoulders on the inner side of said casing, and additional supporting members mounted on said shoulders to engage the bottom of said pot. 85

7. In a device of the class described, the combination of a furnace, an elongated solder pot mounted over said furnace, a fuel oil burner at one end of said furnace for directing a flame along said solder pot, a reservoir for supplying fuel oil to said burner, and means for by-passing the furnace gases for heating the oil in said reservoir. 90

8. In a device of the class described, the combination of a battery of furnaces for heating solder pots and the like, a fuel oil burner for each of said furnaces, a common fuel reservoir for said burners, and means for by-passing the furnace gases given off by the furnaces to heat the fuel oil in said reservoir. 105

This specification signed this 20th day of October, 1926.

WILLIAM BEDDIE ROBERTSON.
